234,075

CARTON PARTITION UNIT

Hile A. Clark, Kirkwood, Mo., assignor to Olinkraft, Inc.

Filed July 14, 1972, Ser. No. 271,917

Term of patent 14 years

U.S. Cl. D9—99   Int. Cl. D9—99

FIG. 1

FIG. 2

FIG. 3

FIG. 4

FIG. 5

FIG. 1 is a perspective view of a carton partition unit showing my new design;

FIG. 2 is a side elevational view;

FIG. 3 is an elevational view looking from the left of FIG. 2;

FIG. 4 is a top plan view; and

FIG. 5 is a bottom plan view thereof.

The sides opposite those seen in FIGS. 2 and 3 are the same in appearance as the respective sides shown.

I claim:

The ornamental design for a carton partition unit, substantially as shown and described.
